MOLDED STOP MECHANISM FOR SLIDING CLASP FASTENERS

Everett E. Day, Andover, Mass., assignor to The Bolt Company, Lawrence, Mass., a corporation of Massachusetts

Application March 13, 1946, Serial No. 654,099

4 Claims. (Cl. 24—205.11)

1

This invention relates to improvements in top stops for sliding clasp fasteners having a pair of stringers provided with complementary series of interlocking elements adapted to be moved into and out of interlocking engagement by a slider.

One of the objects of the invention is to provide a top stop construction having complementary stop members which when assembled will hold the interlocking elements of the respective stringers in suitably spaced relation to facilitate the movement of the slider with preferably detachable means for securing the top stop members in engagement.

A further object of the invention is to provide a construction in which the interlocking members of both stringers and the complementary stop members can be simultaneously molded upon the respective stringers thereby eliminating all problems of location and providing a relatively inexpensive construction.

A further object of the invention is to provide a top stop mechanism of thermoplastic material which will be corrosion-proof.

Another object of the invention is to provide a sliding clasp fastener in which the interlocking elements and the top stop members are of the same corrosion-proof thermoplastic material adapted simultaneously to be molded upon the stringers and in which the material being molded under relatively high pressure will impregnate the material of the stringer and adhere thereto with maximum firmness.

A further object of the invention is to provide a construction of the character above described in which the interlocking elements and the stop members can be so molded as not to have sharp edges which will damage or cut the fabric of the stringer.

A further object of the invention is to provide a construction of the character described which can be molded with a minimum of waste of material.

Another object of the invention is to provide a top stop which is ornamental, efficient and durable.

These and other objects and features of the invention will more fully appear from the following description and the accompanying drawings and will be particularly pointed out in the claims.

A preferred embodiment of the invention is illustrated in the accompanying drawings, in which:

Fig. 1 illustrates end portions of stringers having complementary interlocking elements and converging stop members releasably held in engagement with each other by a locking member;

the top stop assembly being shown in inverted position;

Fig. 2 is a plan view of the edge portion of the stringer having one of the symmetrical stop members secured thereto;

Fig. 3 is a side elevation of the construction shown in Fig. 1 viewed from beneath;

Fig. 4 is an end elevation of Fig. 2 viewed from the left toward the right, the beaded edge portion of the stringer being shown in section;

Fig. 5 is an end view of the locking member; and

Fig. 6 is a plan view of one of the cooperating dies for simultaneously molding the interlocking members and the stop members upon the respective stringers, and also for molding the locking member.

The sliding clasp fastener construction shown in Fig. 1 comprises stringers 1 and 2, preferably of fabric, having respectively beaded edges 3 and 4 and provided respectively with interlocking elements 5 and 6 of thermoplastic material having leg portions 7 and 8 molded upon and embracing the respective beaded edge portions of the stringers 1 and 2 and impregnating the material of the stringers. Complementary stop members 9 and 10 of thermoplastic material are molded upon and embrace the edge portions of the respective stringers 1 and 2 and extend mainly in longitudinal parallelism therewith, as shown in Fig. 2. The upper end portions 11 of each of the complementary stop members are symmetrically convergingly inclined toward the respective edges of the stringer, as illustrated in Fig. 2, so that when the edges of the respective stringers are in abutting position, as illustrated in Fig. 1, the end portions of the stringers embraced by the stop members converge, as illustrated in Fig. 1, while the portions of the stringers having the respective series of interlocking elements are in properly spaced open position.

Suitable preferably detachable locking means is provided for retaining the inclined upper end portions of the stop members in abutting position.

In the particular construction above described the upper and lower faces of the respective stop members are provided with parallel recesses 12 extending inwardly and terminating at the bases 13 of the inclined end portions and like channels 14 and 15 extend inwardly from the lower end portions of the respective stop members to the bases 13 of the end portions in parallelism with the inclined end edge portions 11 thereby providing a web 16 forming a T-shaped tenon

17 which when the stop members are assembled, as illustrated in Fig. 1, extends in parallelism with and upon opposite sides of the vertical plane of the abutting end portions of the stop members.

Any suitable means may be provided for retaining the stop members in the assembled position illustrated in Fig. 1. In the preferred construction the locking member which is illustrated in Fig. 5 comprises a preferably rectangular block 18 having opposite T-shaped longitudinal grooves 19 and 20 providing an H-shaped construction having inwardly extending flanges 21 adapted to engage the respective upper and lower channels 14 and 15 in the respective stop members. When the stop members are brought into abutting position illustrated in Fig. 1 and the locking member 18 slid longitudinally upon the respective webs 16 of the stringers the engagement of the flanges 21 of the locking member with the channels 14 in the stop members will hold the locking members firmly in assembled position.

Preferably suitable means are provided to prevent the locking member from becoming easily disengaged from the stop members. A convenient means illustrated herein comprises projections 22 which project outwardly from the lower end of the surfaces of the web 16 either upon one or both of said surfaces. Such projections will prevent the locking member from being easily slid from locking position but when sufficient force is applied to the locking member will enable it to be disengaged from the stop members. Such projections also will serve to engage the walls of the passages of the slider and hold the slider in engagement with the top stop so that it will not be accidentally displaced.

As before stated one of the objects of the invention is to provide a sliding clasp fastener construction in which the interlocking elements and the top stops, and preferably also the locking member, can be simultaneously cast, preferably by injection molding, upon the edges of both stringers, suitable thermoplastic material being employed which is capable of impregnating the fabric of the stringers and fixedly uniting the same thereto. Suitable molds for thus molding the interlocking elements and the top stop members upon the stringers are illustrated in Figs. 6, 7, and 8 of the drawings. As shown in Fig. 6 the mold comprises complementary rectangular blocks of suitable material, such as steel, each of which is provided with parallel longitudinal shallow recesses 23 and 24 to receive the respective stringers and grooves 25 and 26 to receive the beaded edges of the respective stringers and having a series of suitably spaced parallel cavities 27 and 28 for the respective interlocking elements extending over the grooves 25 and 26 to provide for the legs of the interlocking elements and the heads of the interlocking elements extending toward each other beyond said grooves. Each of the mold section is also provided with suitable complementary mold cavities 29 and 30 for the respective stop members which likewise extend over the grooves 25 and 26 so that the stop members will embrace the edges of the respective stringers.

In the construction illustrated in Fig. 6 the dies also are provided with complementary cavities 31 for forming the H-shaped locking member. The lower die, and if desirable the upper die also, is provided with a longitudinal runner 32 having gates 33 extending therefrom to the cavities 27 and 28 respectively of the interlocking elements

and gates 34 communicating with the cavities of the respective stop members and also with gates 35 leading to the cavity 31 of the stop member. The thermoplastic material when suitably heated to fluid consistency may be introduced into the mold through a suitable sprue 36 preferably in the upper mold member.

It will be obvious that by reason of the present invention complementary interlocking elements and also stop members can be simultaneously and economically cast or applied by injection molding upon the respective stringers and the locking member also molded at the same time.

When the stringers are removed from the mold the material of the runner and the gates can be readily broken away, ground, melted and again utilized for the same purposes. Any roughness upon the edges of the interlocking members and the stop members can be readily ground away and the surface polished in a usual manner, whereupon the stringers with the stop members can be attached to separate edge portions of a garment, the stop members fastened together by the locking mechanism with a minimum of expense and effort.

It will be understood that the particular embodiment of the invention shown and described herein is of an illustrative character and is not restrictive and that various modifications in construction and arrangement of parts may be made within the spirit and scope of the following claims.

Having thus described the invention, what is claimed as new, and desired to be secured by Letters Patent, is:

35 1. A top stop for sliding clasp fasteners for holding the stringers in properly spaced relation to facilitate the movement of the slider upon the complementary series of interlocking elements thereof comprising a top stop assembly having 40 complementary stop members of thermoplastic material longitudinally embracing and fixedly secured to the marginal edges of the upper end portions of the respective stringers and having at the inner edges of their upper end portions abutting flat faces lying in a longitudinal plane 45 centrally between said stringers and in parallelism with the path of the slider, front and rear channels in said members extending in parallelism with the plane of said flat faces providing T-shaped tenons therebetween, and a locking member having longitudinal channels slidably engaging said T-shaped tenons of both stop members releasably securing said stop members to each other and adapted to arrest the slider when moved into engagement therewith.

50 2. A top stop for sliding clasp fasteners for holding the stringers in properly spaced relation to facilitate the movement of the slider upon the complementary series of interlocking elements thereof comprising a top stop assembly having 55 complementary stop members of thermoplastic material longitudinally embracing and impregnating the marginal edges of the upper end portion of the respective stringers and having at the inner edges of their upper end portions abutting flat faces lying in a plane centrally between said stringers and in parallelism with the path of the slider, front and rear channels in said members extending in parallelism with the plane of said

60 65 70 75 flat faces providing T-shaped tenons therebetween, and locking member having substantially an H-shaped cross section and longitudinal channels slidably engaging said T-shaped tenons of both stop members releasably securing said stop members to each other and adapted to arrest

the slider when moved into engagement therewith.

3. A top stop for sliding clasp fasteners as defined in claim 1, in which the web of the T-shaped tenon is provided with projections to prevent the locking member from being readily slid from locking position and to hold the slider in engagement with the top stop so that it will not be accidentally displaced.

4. A stop assembly for slide fasteners of the class described, comprising a pair of complementary stop members with one secured to the marginal edges of each of the respective stringers and having abutting edges lying centrally between said stringers in parallelism with the path of the slider, said stop members constructed and arranged so as to diverge inwardly whereby the stringers are held a spaced distance apart on the side of the stop toward the slider, a locking member for engagement with said complementary stop members for holding the stringers securely together at one end of the fastener, said locking member having interlocking means carried thereby which engages with corresponding interlocking means carried by the respective complementary stop members.
